UNITED STATES PATENT OFFICE.

THEODORE L. PETERSON, OF LEWISTON, MINNESOTA, ASSIGNOR OF ONE-HALF TO
E. N. PETERSON, OF WAUSAU, WISCONSIN.

CONCRETE BUILDING.

Application filed May 2, 1924. Serial No. 710,600.

The present invention has for its purpose to provide, in a concrete building, a construction consisting of corner and intermediate posts rising from a foundation of concrete, in conjunction with wall slabs engaging with the corner and intermediate posts in connection with means on the foundation for holding the corner posts and slabs in position, there being means at the upper ends of the posts for retaining a roof in place as supported on the four walls of the building.

Another purpose is the provision of means for connecting side standards and top and base for supporting and retaining a window frame in position, the frame including the usual sashes, said top and base and posts having connections similar to those of the slabs and the posts for receiving the wall slabs. It is obvious that a door opening may be constructed in a similar manner.

Still another purpose is the provision of beams, preferably of concrete, converging from the tops of the corner posts and connecting with a central beam, in conjunction with upstanding bolts carried by the upper ends of the corner and intermediate posts for engaging with the converging beams, similar bolts being provided for connecting the converging beams and the longitudinal central beam, such beams constituting means for supporting a roof, preferably of sheet metal.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

45 In the drawings:

Figure 1 is a view in front elevation of the concrete building, preferably representing a garage although it is obvious that the same construction may be employed for constructing other characters of buildings.

Figure 2 is a view in side elevation.

Figure 3 is a horizontal sectional plan view of the building on line 3-3 of Figure 2.

Figure 4 is a vertical sectional view on line 55
4-4 of Figure 2.

Figure 5 is an enlarged detail perspective view of the beams for supporting the roof.

Figure 6 is an enlarged detail perspective view of one corner of the foundation and 60 the wall slabs and the lower end of one corner post, looking down in a direction on one corner of the foundation and looking up toward the lower end of one of the corner posts and a wall slab.

Figure 7 is an enlarged view of the perpendicular and horizontal beams for causing the window opening 23 to be formed.

Figure 8 is a detail perspective view of one corner of the connection between the 70 beams 25 and 27 which provide for the support of the window frame 24.

Figure 9 is an enlarged detail sectional view of one corner of the structure showing 75 how the corner posts are supported in position.

Figure 10 is a horizontal sectional view somewhat similar to that in Figure 3, with the exception that the walls are of double thickness, in fact, the upright posts have 80 double channels for the reception of the concrete slabs 20.

Referring to the drawings, 1 designates the foundation constructed preferably of concrete and which may be any proportions and shape, preferably rectangular in plan, and consists of the longitudinal and transverse foundation beams or supports 2 and 3. The upper edges of the supports or beams 2 and 3 have grooves 4 and 5, and 6 and 7 designate the corner and intermediate posts of the building, while 8 designates the posts which bound a door opening 9 for double swinging doors 10 which are mounted upon hinges, as at 11. The doors 10 may be any suitable construction, preferably of wood or metal, and are provided with paneled window lights 12.

It will be noted that the upper edge of the longitudinal and transverse supports or beams of the foundation have depressed seats or recesses 13 and 14 which receive the intermediate, hinged and corner posts 7, 8 and 6. In fact, the upper edge of the foundation is preferably flush with the upper surface of the ground, permitting a motor-driven vehicle to pass through the double door opening 9 without any obstructions.

The interior of the building, which in the present instance is preferably a garage, has its floor surface concreted, as at 15, said surface being flush with the upper edge of the 5 foundation.

Embedded in the longitudinal and transverse beams or supports of the foundation are the heads 16 of anchor studs 17 which rise from the bottoms of the depressed seats 10 or recesses 13 and 14. These bolts enter openings 18 of the lower ends of the corner and intermediate posts, thereby holding the posts perpendicularly.

It will be noted that the intermediate 15 posts 7 have opposite faces provided with grooves 19 which receive the wall slabs of concrete 20, the lower edges of the lowermost slabs being engaged in the grooves 4 of the longitudinal beams or supports of the 20 foundation. The corner posts have their faces, those which are at right angles to each other, provided with grooves 21 which also receive certain of the wall slabs 20. The 25 lower edges of the lowermost slabs which engage with the grooves 21 also enter grooves of the foundation. In fact, the lower edges of the lowermost slabs at the ends of the building enter the grooves 5 of the transverse beams or supports of the foundation. 30 The hinged posts 8 each has a groove 22 on one face which receive certain other of the wall slabs.

In order to provide a window opening 23 for the support of a window frame 35 24, top, base and side or perpendicular beams 25, 26 and 27 are provided. These beams are arranged in rectangular formation and are connected by bolts 28 embedded in the top and base beams to enter the perpendicular 40 side beams to retain the beams in position. The remote faces or edges of these beams 25, 26 and 27 have grooves 29, 30 and 31 for the reception of certain of the wall slabs. It will be noted that a door opening is similarly 45 constructed with the exception that the base beam 26 is omitted and the side or perpendicular beams have holes or depressions in their lower ends to receive bolts 32 embedded in and rising from the foundation.

Rising from the upper terminals of the corner and intermediate posts and having 50 their heads embedded in the posts are bolts 33 which enter depressions or holes in the roof beams 34 which converge toward the top of the roof and have their upper converged 55 terminals connected by similar bolts 35 to a longitudinal central beam 36. These roof beams constitute means for supporting a roof 37 of sheet metal, as in Figure 2, or 60 of concrete which is constructed in sections overlapped, as in Figures 1 and 4, and secured to the beams in any suitable manner (not shown).

It will be noted that the wall slabs are 65 constructed with restricted upper and lower

edges, as at 38, to permit the wall slabs to overlap in the same manner as lap boards to enable the wall slabs to shed the rain and snow and to prevent, to a substantial degree, the seeping in of the moisture. 70

In Figure 10, it will be noted that the posts 6, 7 and 8 have double grooves 19 for the reception of the concrete slabs 20, thereby constructing a building with double thicknesses of such slabs. 75

The invention having been set forth, what is claimed is:

1. A concrete building structure comprising a base of angular formation consisting of longitudinal and transverse beams provided with grooves in their upper faces, with depressed seats at uniformly spaced points, the level of the bottom of said seats being the same as the level of the bottom of the grooves and the seats opening at the outer sides of said base beams, corner and intermediate upstanding posts seated in said seats with their outer faces flush with the outer faces of the base beams, the posts being provided with longitudinal grooves in their side faces, wall slabs disposed in superposed relation between the posts and having their ends seated in the grooves of said posts with the lower edges of the bottom-most slabs seated in the grooves of the base beams, and a roof supported on 80 said posts. 85

2. A concrete building structure comprising a base of angular formation consisting of longitudinal and transverse beams provided with grooves in their upper faces, with depressed seats at uniformly spaced points, the level of the bottom of said seats being the same as the level of the bottom of the grooves and the seats opening at the outer sides of said base beams, corner and intermediate upstanding posts seated in said seats with their outer faces flush with the outer faces of the base beams, the posts being provided with longitudinal grooves in 90 their side faces, wall slabs disposed in superposed relation between the posts and having their ends seated in the grooves of said posts with the lower edges of the bottom-most slabs seated in the grooves of the base beams, the wall slabs above the lowermost slabs each having its lower edge disposed in overlapping relation with the upper edge of the next lower slab, and a roof supported on 95 said posts. 100

3. A concrete building structure comprising a base of angular formation consisting of longitudinal and transverse beams provided with grooves in their upper faces, with depressed seats at uniformly spaced points, the level of the bottom of said seats being the same as the level of the bottom of the grooves and the seats opening at the outer sides of said base beams, corner and intermediate upstanding posts seated in said 105

seats with their outer faces flush with the outer faces of the base beams, the posts being provided with longitudinal grooves in their side faces, wall slabs disposed in superposed relation between the posts and having their ends seated in the grooves of said posts with the lower edges of the bottom-most slabs seated in the grooves of the base beams, and a roof supported on said posts, the base beams being provided with anchor studs embedded in them below said depressed seats and said studs extending upwardly through said seats and into the posts.

In testimony whereof he affixes his signature.

THEODORE L. PETERSON.
